UNITED STATES PATENT OFFICE.

IRVING M. CRAFTS, OF PORTLAND, CONNECTICUT, ASSIGNOR TO THE PICKERING GOVERNOR CO., OF PORTLAND, CONNECTICUT, A CORPORATION.

GOVERNOR.

Application filed April 5, 1928. Serial No. 267,601.

This invention relates to an improvement in centrifugal governors particularly designed for use in connection with internal combustion engines but not so limited.

5 The object of this invention is to provide a simple, efficient and compact centrifugal governor constructed with particular reference to superior sensitiveness and responsiveness to speed changes.

10 In the accompanying drawings:

Fig. 1 is a side view of a governor constructed in accordance with my invention;

Fig. 2 is a sectional view on the line 2—2 of Fig. 1;

15 Fig. 3 is a side view showing the weights and means for connecting them with a governor-sleeve;

Fig. 3^a is a similar view but showing the parts in the positions due to them when the 20 weights are rocked outward by centrifugal force;

Fig. 4 is a top view of the same;

Fig. 5 is an under-side view of the same;

Fig. 6 is an edge view of the same;

25 Fig. 7 is a sectional view on the line 7—7 of Fig. 4;

Fig. 8 is a sectional view on the line 8—8 of Fig. 4;

Fig. 9 is a sectional view on the line 9—9 30 of Fig. 7;

Fig. 10 is a perspective view of one of the weights detached;

Fig. 11 is a perspective view of the governor-sleeve detached; and

35 Fig. 12 is a perspective view of the yoke detached.

In carrying out my invention, I employ a spindle 15 adapted at its lower end 16 to be connected with the moving part of an engine.

40 Threaded onto the spindle is a head 17 which may be fixed to the spindle by a pin 18. Beyond the head, the spindle is reduced in diameter and enters the bore 19 of a sleeve 20 which is formed at its lower end on opposite sides 45 with outwardly-projecting fingers 21. The outer end 22 of the sleeve is reduced in diameter to enter a ball-bearing ring 23 which is surrounded by a ring 24 spaced from it to provide raceways for anti-friction balls

50. On opposite sides are weights 26 and 27 formed with inwardly-projecting lifting-fingers 28 formed with perforations 29 through which lifting-pins 30 extend to bear

against the under-faces of the fingers 21. The perforations 29 are doubly beveled so 55 that the pins have a certain amount of rocking movement, as shown in Fig. 9, to equally bear against the fingers 21, the pins 30 being secured in the finger 28 by locking-pins 31, the ends of which are turned to hold them in 60 place. These weights are formed in their lower faces on opposite sides of the lifting-finger 28 with notches 32 for the reception of the ends of weight-mounting springs 33 and 34 which are connected with the weights by 65 screws 35. The springs 33 extend below the lifting-pins 30 and are seated in notches 36 in the head 17 and between the springs 33 and 34 are spacing-blocks 37 and over the springs 34 are clamping-plates 38, the plates and 70 blocks being secured to the head by screws 39 which pass through the springs. Extending transversely through the weights are perforations 40 for the location of pins 41 and 42 which are connected together by springs 43 and 44 which tend to draw the weights together. The head 17 is suitably mounted in 75 a casing 45 provided with a cap-piece 46 and mounted in this cap-piece is a shaft 47 to which means for controlling the engine are 80 connected. Pinned to this shaft 47 is a yoke 48 which extends into line with and so as to be engaged by the ring 24 and so that as that ring is raised or lowered, the yoke will be 85 rocked to move the shaft 47. Connected with the yoke and with a worm-gear 49 on the shaft 47 is a tension-spring 50 and mounted in the cap and engaging with the worm-gear 49 is a worm 51 on a shaft 52, one end 53 of which projects outward through the cap in convenient position to be turned, whereby the tension of the spring 50 may be adjusted.

90 As the speed of the spindle 15 increases by the action of the engine, centrifugal force tends to move the weights 41 and 42 outward, 95 causing the pins 30 to lift the sleeve 20 and the lifting of the sleeve 20 moves the yoke 48 and turns the shaft 47 accordingly, and this lifting of the sleeve may be regulated to a certain extent by the tension on the spring 50, which also tends to depress the yoke and hence turn the shaft 47 to its normal position. The springs 33 and 34 provide substantially-frictionless pivots for the weights and, 100 at the same time, exert controlling influence 105 on the weights.

I thus provide, in a very compact manner, a governor particularly designed for the control of a prime mover.

I claim:

5. 1. A centrifugal governor, comprising a rotatable spindle; a pair of flexible converging reversely-bowed complementary sheet-metal mounting-springs carried by the said spindle and transversely-disposed with respect thereto; a weight secured to the converging ends of the said springs and supported thereby with capacity for rocking movement toward and away from the said spindle; spring-means arranged to yieldingly hold the said weight inward toward the said spindle; and means for transmitting the movement of the said weights to the mechanism to be governed.
10. 2. A centrifugal governor, comprising a rotatable spindle; a head secured thereto; a pair of flexible converging reversely-bowed complementary sheet-metal mounting-springs carried by the said head and hence by the said spindle and transversely-disposed with respect to the said spindle; a weight secured to the converging ends of the said springs and supported thereby with capacity for rocking movement toward and away from the said spindle; spring-means arranged to yieldingly hold the said weight inward toward the said spindle; and means for transmitting the movement of the said weights to the mechanism to be governed.
15. 3. A centrifugal governor, comprising a rotatable spindle; a pair of flexible reversely-bowed complementary sheet-metal mounting-springs carried by and transversely-disposed with respect to the said spindle and having their opposite ends converging; a weight secured to each of the converging opposite ends of the said springs and supported thereby with capacity for rocking movement toward and away from the said spindle; spring-means extending between the weights at the respective opposite ends of the said springs and normally urging them inward toward the said spindle; and means for transmitting the movement of the said weights to the mechanism to be governed.
20. 4. A centrifugal governor, comprising a rotatable spindle; a head secured thereto; a pair of flexible reversely-bowed complementary sheet-metal mounting-springs carried by the said head and transversely-disposed with respect thereto; a weight secured to each of the converging opposite ends of the said springs and supported thereby with capacity for rocking movement toward and away from the said spindle; spring-means extending between the weights at the respective opposite ends of the said springs and normally urging them inward toward the said spindle; and means for transmitting the movement of the said weights to the mechanism to be governed.
25. 5. A centrifugal governor, comprising a rotatable spindle; two pairs of flexible converging reversely-bowed complementary sheet-metal mounting-springs respectively carried by the said spindle on each of the opposite sides thereof and transversely-disposed with respect thereto; a weight secured to the converging ends of the said pairs of springs and supported thereby with capacity for rocking movement toward and away from the said spindle; spring-means extending between the weights at the respective opposite ends of the said springs and normally urging them inward toward the said spindle; and means for transmitting the movement of the said weights to the mechanism to be governed.
30. 6. A centrifugal governor, comprising a rotatable spindle; a pair of flexible laminated converging reversely-bowed complementary sheet-metal mounting-springs carried by the said spindle and transversely-disposed with respect thereto; a weight secured to the converging ends of the said springs and supported thereby with capacity for rocking movement toward and away from the said spindle; spring-means arranged to yieldingly hold the said weights inward toward the said spindle; and means for transmitting the movement of the said weights to the mechanism to be governed.
35. 7. A centrifugal governor, comprising a rotatable spindle; a pair of flexible reversely-bowed complementary sheet-metal mounting-springs carried by the said spindle and transversely-disposed with respect thereto; a weight secured to the converging ends of the said springs and supported thereby with capacity for rocking movement toward and away from the said spindle; spring-means arranged to yieldingly hold the said weights inward toward the said spindle; and means for transmitting the movement of the said weights to the mechanism to be governed.
40. 8. A governor, comprising a spindle, a head mounted thereon, a pair of double-ended flexible reversely-bowed complementary sheet-metal mounting-springs carried by said head, a sleeve slidable on said spindle and formed on opposite sides with fingers, two weights arranged on opposite sides of the sleeve and secured respectively to the opposite ends of the said mounting-springs; and formed with inwardly-projecting arms, pins mounted in said arms and bearing on the under-side of said fingers, upper and lower springs connecting the lower ends of the weights, the lower springs extending beneath the lifting-pins, governor-springs tending to draw the two weights together, a governor-

- shaft above said sleeve, a yoke pinned to said shaft and extending over said sleeve and adapted to be moved thereby, and a spring on said governor-shaft tending to return it 5 to its normal position.
9. A governor, comprising a spindle, a head mounted thereon, a pair of flexible double-ended reversely-bowed complementary sheet-metal mounting-springs carried by said 10 head, a sleeve slideable on said spindle and formed on opposite sides with fingers, two weights arranged on opposite sides of the sleeve and secured respectively to the opposite ends of the said mounting-springs and 15 formed with inwardly-projecting arms, pins mounted in said arms and bearing on the under-side of said fingers, upper and lower springs connecting the lower ends of the weights, the lower springs extending beneath the lifting-pins, governor-springs tending to 20 draw the two weights together, a governor-shaft above said sleeve, a yoke pinned to said shaft and extending over said sleeve and adapted to be moved thereby, a spring on said governor-shaft tending to return it to its nor- 25 mal position, and means, including a worm-gear and worm, for applying tension to said spring.

In testimony whereof, I have signed this specification:

IRVING M. CRAFTS.
